CLAIM

The ornamental design for a container cap, as shown and described.

DESCRIPTION

FIG. 1 is a rear isometric view of a container cap showing the design.

FIG. 2 is a front isometric view of the container cap of FIG. 1.

FIG. 3 is a rear elevation view of the container cap of FIG. 1.

FIG. 4 is a front elevation view of the container cap of FIG. 1.

FIG. 5 is a left side elevation view of the container cap of FIG. 1.

FIG. 6 is a right side elevation view of the container cap of FIG. 1.

FIG. 7 is a top plan view of the container cap of FIG. 1.

FIG. 8 is a bottom plan view of the container cap of FIG. 1; and,

FIG. 9 is a bottom isometric view of the container cap of FIG. 1.

The dashed lines shown in the drawings illustrate portions of the container cap that are not claimed and thus form no part of the claimed design. The shading lines shown in the drawings represent the three-dimensional contour of the claimed design and are not intended to indicate surface decoration.

1 Claim, 5 Drawing Sheets
